[57] CLAIM

The ornamental design for apparatus for preparing specimens for histological examination, substantially as shown and described.

DESCRIPTION

FIG. 1 is a front perspective view of apparatus for preparing specimens for histological examination, showing my design;

FIG. 2 is a top plan view;

FIG. 3 is a rear elevation view;

FIG. 4 is an elevation view, looking from the right of FIG. 2; and

FIG. 5 is an elevation view looking from the left of FIG. 2.

FIG. 1

FIG. 2

FIG. 3

FIG. 4

FIG. 5
